Filed June 3, 1968, Ser. No. 12,184

Term of patent 14 years

Int. Cl. D6—01

U.S. Cl. D33—27

FIG. 1 is a perspective view of a toothbrush and dentifrice holder for bathrooms embodying my new design;
FIG. 2 is a front elevation thereof;
FIG. 3 is an end elevation thereof;
FIG. 4 is a top plan view thereof; and
FIG. 5 is a cross sectional view taken on the line 5—5 in FIG. 4, the back portion thereof being omitted for convenience of illustration.

The dominant features of my design reside in the portions shown in full lines.

I claim:
The ornamental design for a toothbrush and dentifrice holder for bathrooms, as shown and described.
